US00D891498S

(12) **United States Design Patent** (10) Patent No.: **US D891,498 S**
Masuda et al. (45) Date of Patent: ** Jul. 28, 2020

(54) **VEHICLE-MOUNTED STEREO CAMERA**(71) Applicant: **Hitachi Automotive Systems, Ltd.**,
Hitachinaka-shi, Ibaraki (JP)(72) Inventors: **Keisuke Masuda**, Ibaraki (JP);
Yoshiyuki Sasada, Ibaraki (JP);
Masaaki Fukuhara, Ibaraki (JP)(73) Assignee: **Hitachi Automotive Systems, Ltd.**,
Hitachinaka-shi (JP)(**) Term: **15 Years**(21) Appl. No.: **29/663,978**(22) Filed: **Sep. 20, 2018**(30) **Foreign Application Priority Data**

Mar. 21, 2018 (JP) 2018-005976

CLAIM

The ornamental design for a vehicle-mounted stereo camera, as shown and described.

DESCRIPTION

FIG. 1 is a front, top and right side perspective view of a vehicle-mounted stereo camera according to the design;

FIG. 2 is a rear, bottom and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines illustrate portions of the vehicle-mounted stereo camera that form no part of the claimed design.
